(57) **CLAIM**

The ornamental design for a slotwall hanger bracket, as shown and described.

DESCRIPTION

FIG. 1 is a right front perspective view of the design of the hanger bracket;

FIG. 2 is a front elevational view thereof. The ornamental design is not visible in a rear view;

FIG. 3 is a right side elevational view thereof, the left side elevational view being a mirror image; and,

FIG. 4 is a top plan view thereof, the bottom view being a mirror image.

Those portions of the hanger bracket in broken lines, specifically the surfaces of the hanger bracket that extend back from the front of the hanger bracket from the top and bottom edges of the hanger bracket are for illustrative purposes only and form no part of the claimed design.

The broken lines showing a hook on the front of the hanger bracket are an example of an environmental structure for illustrative purposes only and forms no part of the claimed design.
